(57) **CLAIM**

The ornamental design for a jump seat frame, as shown and described.

DESCRIPTION

FIG. 1 is a perspective view of a jump seat frame, showing my new design;

FIG. 2 is a front elevational view thereof, with the rear and side elevational views thereof being mirror images; and, FIG. 3 is a top plan view thereof, showing my new design. The broken lines showing of the baby jump seat in FIG. 1 are for illustrative purposes only and form no part of the claimed design.
